HOUSE

Donald J. Scholz, Toledo, Ohio, assignor to Scholz Homes,
Inc., Toledo, Ohio, a corporation of Ohio

Filed June 22, 1962, Ser. No. 70,653

Term of patent 14 years

(Cl. D13—1)

FIG. 1 is a front perspective view of a house embodying my new design;

FIG. 2 is a front perspective view of the house;

FIG. 3 is an elevational view of the left side of the house in reduced scale;

FIG. 4 is a right side elevational view in reduced scale;

FIG. 5 is a rear elevational view in reduced scale;

FIG. 6 is a top plan view of the house in still further reduced scale; and

FIG. 7 is a perspective front elevational view of the house.

For convenience of illustration, only parts of the brick surfaces have been shaded in the several views of the drawings. It is to be understood that these surfaces continue throughout the areas indicated.

The modified design of FIG. 7 is identical to the design of FIGS. 1 through 6 except that the garage door is eliminated from the left side of the house and is located at the front side thereof.

I claim:

The ornamental design for a house, as shown and described.
